THOMAS HARRISON SANFORD, OF ALEXANDER CITY, ALABAMA, ASSIGNOR OF ONE-
FOURTH TO LEMUEL B. COLEY, OF ALEXANDER CITY, ALABAMA.

LATCHING DEVICE FOR CAR-COUPLEDGS.

1,369,358.

Specification of Letters Patent. Patented Feb. 22, 1921.

Application filed January 15, 1920. Serial No. 351,601.

To all whom it may concern:

Be it known that I, THOMAS HARRISON SANFORD, a resident of Alexander City, in the county of Tallapoosa and State of Alabama, have invented certain new and useful Improvements in Latching Devices for Car-Couplings, of which the following is a specification.

My invention relates to car couplings and particularly to a latching means therefor for effectively securing the draw-heads of the coupling together so as to prevent their accidental release and to eliminate the unnecessary slack which is found in couplings now in use.

It is also a purpose of my invention to provide a latching device of simple, durable and efficient construction which in its released position is capable of being moved to a locking position when the two draw-heads are moved into engagement with each other.

I will describe one form of coupling and one form of latching device embodying my invention, and will then point out the novel features thereof in the claim.

In the accompanying drawings:

Figure 1 is a view showing in top plan and partly in section one form of coupling, including one form of latching device, embodying my invention, the latter being shown in the released position.

Fig. 2 is a view similar to Fig. 1 with the latching device in locking position.

Fig. 3 is a view showing in side elevation the coupling shown in Fig. 1.

Fig. 4 is a fragmentary sectional view of the draw-bar showing the manner in which the locking block is mounted therein.

Similar reference characters refer to similar parts in each of the several views.

Referring specifically to the drawings, D designates a draw-bar on one end of which is formed a draw-head H. The draw-head H is of the Janney type and is provided with a coupling member K which is pivoted on a pin P so as to swing to locking and releasing positions, as will be understood. The draw-bar D and the draw-head H are bored longitudinally to provide compartments 15 and 16 for the reception of the latching device. As shown in Figs. 1 and 2, the compartment 15 slidably receives the locking block B, the compartment and block being rectangular in contour to prevent rotation of the former within the compartment.

ment. The block B is operatively connected to an actuating lever L through the medium of a rod R, such rod being mounted for sliding movement within both of the compartments 15 and 16 and secured at one of its ends to the block B while its opposite end is pivotally connected to the end of the lever L as at 17. As shown in Fig. 1, the cross-sectional area of the compartment 15 exceeds that of the compartment 16 so as to provide a shoulder at the junction of the two against which bears one end of a coil expansible spring 18. The spring 18 surrounds the rod R and its opposite end abuts the locking block B so that it serves to bias the block in the direction of the draw-head. As shown in Fig. 4, the movement of the locking block B within the compartment 15 is restricted by means of a pin 19 which works within a groove 20 formed in the lower wall of the compartment 15 and a recess 21 formed in the under side of the block B. It will be seen from this arrangement that the pin 19 allows the block B to move the length of the groove 20, further movement being restricted by the engagement of the pin with the end walls of the groove and with the walls of the recess 21.

As shown in Figs. 1 and 2, the coupling member K is provided with a curved arm A which works within a suitable opening formed in the draw-head. This arm A is designed for the purpose of maintaining the locking block B in retracted or released position when the coupling member K is in the inactive position. As shown in Fig. 1 the free end of the arm A engages the block B when the coupling member K is in the inactive position and this prevents outward movement of the block under the action of the spring 18. Because of the curvature of the arm A, it is obvious that the coupling member K can be swung to the active position and when it reaches this active position, the block B is automatically moved forward so as to engage the coupling member and thus lock the same in the active position. In the active position of the block B, it engages a beveled surface 22 of the coupling member K and firmly locks the coupling member in the active position at the same time permitting the unrestricted movement of the block to releasing position.

The releasing and locking positions of the block B as well as the active and inactive

positions of the coupling member K are clearly shown in Figs. 1 and 2 of the drawings. In the locking position of the block B the lever L is swung forwardly as shown 5 in Fig. 2, thus lever L swings about a pivot 23 as a center. When it is desired to move the locking block to the releasing position, the lever L is manually actuated so as to occupy the position shown in Fig. 1 whereby 10 the block B is moved into the compartment 15 and against the tension of the spring 18.

It is to be understood that an identical coupling member is provided to co-act with the coupling member K, such member being 15 shown in phantom in Figs. 1 and 2 and supported by a draw-head and draw-bar identical in construction to members D and H.

Although I have shown and described only one form of car coupling, it is to be 20 understood that various changes and modifications may be made herein without departing from the spirit and scope of the appended claim.

Having described my invention, what I claim is:

A car coupling comprising a draw-bar, a draw-head formed on the bar, said draw-head and draw-bar being bored longitudinally to provide compartments, a coupling member pivoted on the draw-head, a locking block movable within one of said compartments, means for biasing said block to engage said coupling member, means for retracting said block so as to disengage said coupling member, means for limiting the movement of said block in either direction comprising, a pin, a recess formed in said block for receiving said pin, and a groove formed in the bore of said draw-head and also receiving said pin, and an arm formed on the coupling member movable in an arc substantially at right angles to the direction of movement of said block for retaining the block in releasing position when said coupling member is in the inactive position.

THOMAS HARRISON SANFORD.
